STENCILING APPARATUS

Raymond G. Martin, Washington, Pa., assignor
to Solar Laboratories, a corporation of Penn-
sylvania

Application May 10, 1937, Serial No. 141,672

11 Claims. (Cl. 101—114)

The present invention relates to improvements in stenciling apparatus and more particularly to an apparatus which is primarily designed for commercial use in stenciling circular or substantially circular designs of vitreous enamel on the peripheral areas or regions of vitreous or ceramic articles such, for example, as plates, dishes, saucers and the like. The apparatus may, however, be employed in applying a circular design by a stenciling process to any article capable of receiving the same. The invention is concerned with stenciling apparatus of the type employing a mesh screen, portions of which are left open to form the design to be imparted to the articles, and in which a vitreous enamel preparation is poured upon the screen and uniformly spread over and forced through the open portions of the screen and onto the articles by a rubber squeegee.

The principal object of the invention is to provide an apparatus for stenciling which will effectively apply to the articles being treated a continuous closed design in such a manner as to leave no trace of overlap in the design, yet which will insure a closed design having no gap apparent therein.

It is another object of the invention to provide a stenciling machine of the type set forth above which is designed for stenciling the peripheral areas of plates, dishes, saucers and the like, in which there is incorporated a novel means for supporting the articles to be decorated in rolling line contact with the stencil screen.

Other objects of the invention will become more readily apparent hereinafter.

In the accompanying drawings:

Fig. 1 is a longitudinal vertical sectional view taken substantially centrally through an apparatus manufactured in accordance with the present invention;

Fig. 2 is a fragmentary vertical sectional view taken through a portion of the apparatus showing a modified form of article support;

Fig. 3 is a top plan view of the apparatus;

Fig. 4 is a sectional view taken substantially along the line 4—4 of Fig. 1; and

Fig. 5 is a sectional view taken substantially along the line 5—5 of Fig. 3.

The stenciling apparatus is in the form of a machine involving in its general organization a support or table 10 provided with front and rear supporting legs 11 and 12 respectively. Bolted or otherwise secured to the upper surface of the table 10 are a pair of standards 13 which serve to support between their upper ends a horizontal

rock-shaft 14 which is journaled at its ends in bearings 15.

The rock shaft 14 extends across the rear edge of the table 10, is substantially coextensive therewith, and rockably supports the inner or rear end of a stencil screen assembly 16.

A forwardly extending squeegee assembly 17 is similarly supported upon the rock-shaft 14. The assemblies 16 and 17 overlie the table 10.

The stencil screen assembly (Figs. 1 and 3) 10 consists of a triangular plate 18 having integral aligned sleeves 19 formed thereon through which the rock-shaft 14 extends. The plate is centered upon the rock-shaft 14 by means of collars 20 mounted on the rock-shaft outside of and abutting 15 the sleeves 19. The plate 18 is provided with a forwardly extending supporting arm 21 from which there depends adjacent its free end a pivot pin 22, the lower end of which serves to support thereon, by means of anti-friction bearings 23, a 20 central hub member 39 in the form of a circular ring, and in which ring the bearing 23 is fitted. The hub member 39 is nested within an inner ring 68 or collar of a stencil screen unit 24. The hub member 39 and ring 68 are maintained in position, one within the other, by means of a circular face plate 69 which is secured to the upper 25 surfaces of these two members.

The stencil screen unit 24 also includes an outer ring 25 which is concentric with the inner ring 30 68 and is connected thereto by means of a single radial arm or spoke 26 integrally formed on the face plate 69. A ring-like operating wheel 27 encircling and concentric with the stencil screen unit 24 is maintained in spaced relation to the 35 screen ring 25 by spokes 28. A silk stencil screen S or other conventional screen having impervious portions and pervious portions, the latter representing the design to be stenciled on the articles, extends across the opening existing between the 40 inner ring 68 and outer ring 25 and is secured to both of these members in any suitable manner as, for example, by gluing. The level of the inner ring 68 is slightly below the level of the outer ring 25. Thus the stencil screen assumes an obtuse 45 taper or frusto-conical form which is designed to accommodate the tapered or frusto-conical surfaces of the articles undergoing decoration, as will presently appear.

Referring now to Figs. 1 and 3, a forwardly extending bracket 30 is secured to a cross bar 31 which extends across the standards 13 and is provided at its forward end with a downwardly turned arcuate plate 32 having a slot 33 formed therein. A pair of limit stops 34 in the form of 55

- nut and bolt assemblies are adjustably mounted on the plate 32 and are slideable laterally of the apparatus in the slot 33. A pair of circumferentially adjustable abutments 35 in the form of nut and bolt assemblies are adjustably secured in slots 36 formed in the operating wheel 27 and their relative positions on the wheel 27 are determined by the character of the articles undergoing decoration and in a manner presently to be described. The limit stops 34 are positioned in the path of movement of the abutments 35 and are designed to be engaged thereby to limit the amplitude of the oscillation of the stencil screen unit 24.
- 15 In order to adjust the level of the stencil screen unit 24, an adjusting screw 37 extends through a forward extension 38 of the cross bar 31 and engages the underneath side of a limit stop 38 mounted on the underneath side of the plate 18.
- 20 By turning the adjusting screw 37 in one direction or the other, the entire screen unit 24 will be elevated or lowered as the case may be.
- 25 The squeegee assembly 17 consists of a triangular plate 40 having integral aligned sleeves 41 formed thereon through which sleeves the rock-shaft 14 extends. The plate 40 overlies the plate 18 and is centered upon the rock-shaft 14 by means of collars 42 mounted on the rock-shaft inside of the sleeves 41. The plate 40 is provided with a forwardly extending arm 43 having a longitudinal slot 44 formed therein. An adjusting screw 45 extends through the end of the arm 43 and projects into the slot 44. A squeegee supporting rod 46 is provided with a squared end 46 that is adjustably mounted in the slot 44 by means of a clamping nut 47. The end of the adjusting screw 45 projects into, and is rotatably secured in, the squared end 46 of the rod 46 adjacent the top thereof, by means of a pin and groove connection 48. Thus it will be seen that the longitudinal position of the squeegee supporting rod 46 may be adjusted by loosening the nut 47 and turning the adjusting screw 45 in one direction or the other, while at the same time turning of the rod 46 in any adjusted position thereon is prevented.
- 30 Suspended from a bracket 49 carried by the lower end of the squeegee supporting rod 46 is a squeegee S' which is capable of angular adjustment in the bracket 49 by means of a clamping nut and bolt assembly 50.
- 35 The squeegee S' is designed to sweep the peripheral regions of the stencil screen S and in order to adjust the squeegee S' to the stencil screen S and obtain the proper degree of pressure thereon, an adjusting screw 51 passing through the plate 40 of the squeegee assembly 17 engages the arm 21 of the stencil screen assembly 16.
- 40 60 The squeegee assembly 17 is capable of being elevated by the operator in a manner subsequently to be described, to cause the squeegee S' to clear the screen S. Toward this end, a series of counterweights 55 suspended from a short arm 56 formed on one of the sleeves 19 provides a counterbalance for the entire stencil screen assembly 16. A similar series of counterweights 57 suspended from a short arm 58 formed on one of the sleeves 41, provides a counterbalance for the entire squeegee assembly 17. A treadle mechanism (not shown) which projects forwardly of the machine adjacent the bottom thereof in a convenient position for the operator of the machine, operates through a link 59 attached to a short arm 68 formed on the other sleeve 41 to

swing the two assemblies 16 and 17 upwardly about the axis of the rock-shaft 14 when depressed by the foot of the operator. In order to return the squeegee S' to its normal screen-engaging position, a coil spring 52, centered upon a pin 53 carried by the arm 21 and passing through the plate 40, bears against the plate 40 at one end thereof and against a wing nut 54 at the other end thereof. Adjustment of the wing nut 54 will lessen or increase the pressure applied to the squeegee blade 75 upon the screen S.

In the present instance, two forms of article supporting structures are disclosed, either one being suitable for rotatably supporting an article P (which may be a plate or the like) in such a manner that its peripheral regions make tangential rolling line contact with the underneath surface of the stencil screen S.

In Fig. 1, the supporting means for the articles P comprises a plurality of supports 60, 61 and 62 which extend through and are horizontally and vertically adjustable in a plurality of radial slots 63 formed in the table portion 10 of the apparatus. The upper ends of the supports 60 have yokes 64 formed thereon. The supports 60 and 61, together with the yokes 64 thereof, are identical in construction and each yoke serves to pivotally support a bracket 65 upon which there is rotatably mounted a grooved wheel or roller 66 adapted to engage the extreme rim of the article P undergoing decoration and rotatably support the same. The rollers 66 are normally urged inwardly of the plate P toward a common center by means of coil springs 67 which are anchored at their lower ends to plates 70 which are secured in position on the table 10 by means of nuts 87 mounted on the supports 60 and 61, and at their upper ends to extensions 71 formed on the brackets 65. The yoke 64 of the support 62 is in the form of a clamping yoke and serves to adjustably support therein a roller support 72 which carries at its outer end a flanged roller 73 adapted to adjustably support thereon the periphery or rim of the article undergoing decoration. It is to be noted that the elevation of the rollers 66 and 73 in the apparatus is calculated so that the plates supported therebetween occupy an inclined position with the peripheral regions or rim portions thereof in tangential rolling line contact with the underneath surface of the screen.

In Fig. 2, the supporting structure for the article P consists of an article-supporting chuck 75 which is rotatably mounted by means of anti-friction bearings 76 upon the upper end of a short chuck supporting stem 77 which is mounted for angular adjustment upon a bracket 78. The bracket 78 is supported upon the table portion 10 of the apparatus and the position thereof may be adjusted longitudinally of the table 10 by means of clamping nut and bolt assemblies 79 that extend through the bracket 78 and through a slot 80 provided in the table. The chuck is provided with a plate receiving recess 81 in the face thereof to accommodate the base of the plate or other article undergoing decoration. Not only is the inclination of the chuck 75 adjustable to adapt the peripheral regions of the article to the stencil screen in the manner previously described, but, in addition, the chuck 75 is removable from the bracket 78 for the purpose of interchangeability to permit chucks of different sizes to be installed in the apparatus.

In the operation of the apparatus, the proper

adjustment of the article supporting assembly shown in Fig. 1 or of the assembly shown in Fig. 2, as the case may be, is made so that the article is brought into register with the stencil screen S with the peripheral rim portion thereof in tangential rolling line contact with the underneath surface of the screen. The screen S is so designed that the arcuate extent of the pervious portion thereof which represents the design to be applied to the articles, is equal to the circumference of the closed design when applied to the rim portion of the articles. The circumferential positions of the abutments 35 are calculated so that the amplitude of oscillation 10 of the stencil screen unit 24 from one extreme position thereof to the other extreme position thereof, will carry the pervious portion of the screen into contact with the rim portion of the article throughout its entire length, no more 15 and no less. A small quantity of a suitably colored, finely ground, vitreous enamel composition is applied to the stencil screen S in the usual manner, and the screen unit is caused to move from one extreme position thereof to the other extreme position thereof. The squeegee S', being in contact with the screen S, sweeps 20 the pervious portion or design of the screen and forces a portion of the enamel through the screen and onto the rim portion of the article. 25

After the design has thus been applied to the article in this manner, the operator depresses the foot treadle mechanism which, through the medium of the link 59, tilts the entire squeegee assembly 17 about the axis of the rock-shaft 30 35 and elevates the same. Upon such elevation of the squeegee assembly 17, the coil spring 52 is compressed and the squeegee is caused to clear the stencil screen and enamel thereon. Movement of the squeegee assembly upwardly beyond the limit of compression of the spring 52 40 serves to carry the stencil screen assembly 16 upwardly in order that the operator may have access to the decorated article P and substitute an undecorated article in its stead. Upon release 45 of pressure upon the foot treadle mechanism, the stencil screen and squeegee assemblies 16 and 17 are lowered into operative decorating position with the squeegee in contact with the stencil screen S and with the screen in tangential rolling line contact with the peripheral regions 50 of the substituted undecorated article P. The screen unit 24 is oscillated in the reverse direction and the stenciling operation is repeated.

Modifications may be resorted to within the spirit and scope of the appended claims.

I claim:

1. In a stenciling apparatus, a stencil screen provided with a generally arcuate pervious portion extending around a portion of the periphery thereof and representing a closed design to be applied to the peripheral rim portion of a saucer-like article, the extent or length of said arcuate pervious portion being equal to the circumference of the closed design, a squeegee for said screen, and means for supporting said screen and an article to be decorated with the screen and peripheral rim portion of the article in rolling line contact.

2. In a stenciling apparatus, a stencil screen provided with a generally arcuate pervious portion extending around a portion of the periphery thereof and representing a closed design to be applied to the peripheral rim portion of a saucer-like article, the extent or length of said arcuate pervious portion being equal to

the circumference of the closed design, means for supporting an article to be decorated for revolution about its axis, means for supporting said screen for revolution about its central axis with the article and screen in rolling line contact with each other, and means for forcing coloring material through said screen upon oscillation of the same.

3. In a stenciling apparatus, a stencil screen provided with a generally arcuate pervious portion extending around a portion of the periphery thereof and representing a closed design to be applied to the peripheral rim portion of a saucer-like article, the mean extent of said arcuate pervious portion being equal to the mean circumference of the closed design, said pervious portion of the screen being confined within an area of the screen which is a frustum of an obtuse cone of less angularity than the angularity of the obtuse cone within the surface of which the peripheral rim portion of the article lies, means for supporting said screen for oscillation about its central axis, means for supporting said article for revolution about its axis with the frusto-conical peripheral rim portion thereof in rolling line contact with said screen, and means for applying decorating material through said screen and onto said peripheral rim portion.

4. In a stenciling apparatus, a stencil screen provided with a generally arcuate pervious portion extending around a portion of the periphery thereof and representing a closed design to be applied to the peripheral rim portion of a saucer-like article, the mean extent of said arcuate pervious portion being equal to the mean circumference of the closed design, said pervious portion of the screen being confined within an area of the screen which is a frustum of an obtuse cone of less angularity than the angularity of the obtuse cone within the surface of which the peripheral rim portion of the article lies, means for supporting said screen for oscillation about its central axis, means for supporting said article for revolution about its axis with the frusto-conical peripheral rim portion thereof in rolling line contact with said screen, a squeegee in stationary contact with said screen for applying decorating material through said screen and onto said peripheral rim portion, and means for adjustably varying the amplitude of oscillation of said screen.

5. In a stenciling apparatus, a stencil screen provided with a generally arcuate pervious portion extending around a portion of the periphery thereof and representing a closed design to be applied to the peripheral rim portion of a saucer-like article, the mean extent of said arcuate pervious portion being equal to the main circumference of the closed design, said pervious portion of the screen being confined within an area of the screen which is a frustum of an obtuse cone of less angularity than the angularity of the obtuse cone within the surface of which the peripheral rim portion of the article lies, means for supporting said screen for oscillation about its central axis, means for supporting said article for revolution about its axis with the frusto-conical peripheral rim portion thereof in rolling line contact with said screen, a squeegee in stationary contact with said screen for applying decorating material through said screen and onto said peripheral rim portion, an actuating member surrounding said screen and substantially concentric therewith, and a pair of limit stops mounted for

circumferential adjustment on said actuating member and designed to engage a stationary part of the apparatus to vary the amplitude of oscillation of said screen.

5. 6. In an apparatus for applying a closed band of designs to the peripheral rim portions of plates, saucers and the like by a stenciling process, a frusto-conical stencil screen having a generally arcuate pervious portion extending around the 10 side thereof, the mean extent of said arcuate portion being equal to the mean circumference of said closed band of designs to be applied to the peripheral rim portion of an article, means for mounting said screen for oscillation about its axis, 15 means for mounting said article for rotation about its axis, means for raising and lowering said screen into and out of tangential rolling line contact with said rim portion of the article, and means for applying coloring material through said 20 pervious portion of the screen upon oscillation of the screen in either direction.
7. In an apparatus for stenciling continuous designs on plates and like articles, an article support comprising in combination a plurality of 25 supporting rollers adapted to engage the rim of a plate to be decorated at spaced points there-around, one of said rollers having a cylindrical side upon which the margin of said plate is adapted to be supported and an annular flange against 30 which said rim is adapted to bear, others of said rollers each being provided with a peripheral groove in which said rim is adapted to ride, and means normally urging said other rollers inwardly of the plate and against said rim whereby said 35 rim is normally urged into engagement with said flange on the first mentioned roller.
8. In an apparatus for stenciling continuous designs on the frusto-conical rim portions of saucer-like articles, a frusto-conical stencil screen, means 40 for mounting said screen in tangential rolling

line contact with the rim portion of an article to be decorated, and means for forcing coloring material through said screen and onto the rim portion of the article from the inside thereof.

9. In an apparatus for stenciling continuous designs on the frusto-conical rim portions of saucer-like articles, a frusto-conical stencil screen, means for mounting said screen in tangential rolling line contact with the rim portion of an article to be decorated, a stationary squeegee in contact with 10 said screen along the line of contact between the article and screen, and means for limiting the extent to which said screen and article may roll upon each other.

10. In an apparatus for stenciling continuous 15 designs on the frusto-conical rim portions of saucer-like articles, a frusto-conical stencil screen, means for mounting said screen in tangential rolling line contact with the rim portion of an article to be decorated, a stationary squeegee in contact 20 with said screen along the line of contact between the article and screen, and means for adjustably regulating the extent to which said screen and article may roll upon each other.

11. In an apparatus for applying arcuate designs to saucer-like articles by a stenciling process, a stencil screen having a frusto-conical surface provided with a pervious portion representing the design to be applied to an article, means for mounting said screen for oscillation about the 30 axis of said frusto-conical portion thereof, means for mounting an article for rotation about its axis and in tangential rolling line contact with said frusto-conical portion of the screen, and means disposed within said frusto-conical portion of the screen for forcing coloring material through said pervious portion thereof and onto 35 said article.

RAYMOND G. MARTIN. 40
